CLAIM

The ornamental design for a metered dose topical applicator, as shown and described.

DESCRIPTION

FIG. 1 is a perspective view of the metered dose topical applicator with a cap removed. The view from the opposite side being identical thereto. The surface and features as shown continue around the metered dose topical applicator. FIG. 2 is a perspective view of the metered dose topical applicator with the cap in place.

FIG. 3 is a side elevational view of the metered dose topical applicator with the cap removed; and,

FIG. 4 is a top plan view of the metered dose topical applicator with the cap in place.

The bottom view is omitted and features thereon form no part of the claimed design. Any features on the inside of the cap are not shown and form no part of the claimed invention. The broken lines in the figures show portions of the metered dose topical applicator that form no part of the claimed design.

1 Claim, 3 Drawing Sheets
